UNITED STATES PATENT OFFICE

2,421,465

BALING PRESS

George C. Schley, Milwaukee, Wis.

Application October 12, 1944, Serial No. 558,365

2 Claims. (Cl. 100—8)

1

My invention refers to baling presses for paper, rags, leather, rubber, etc. and it has for its object to provide a simple, durable and economically constructed press, having all of the advantages of the more expensive standard type while at the same time a material saving in space and bulk is accomplished both as to the height and body area of the same.

Specific objects of my invention are:

To provide means for filling the box from the top.

To provide a platen having a centrally disposed receiving or loading opening therein with a hinged closure therefor and manually controlled lock and release means.

To provide sliding doors for controlling the bale ejection side openings of the box, whereby economy in lateral space is obtained and pressure strain is uniformly resisted.

With the above and other minor objects in view, my invention consists in certain peculiarities of construction and combination of parts as will be fully set forth hereinafter with reference to the accompanying drawings and subsequently claimed.

In the drawings:

Figure 1 represents a side elevation of a baling press embodying the features of my invention with parts broken away and in section to more clearly illustrate structural features, the section being generally indicated by line 1—1 of Figure 3.

Figure 2 a top plan view of the same with parts broken away and in section to more clearly illustrate details of construction with a special reference to the toggle link platen actuating mechanism.

Figure 3 a longitudinal sectional elevation through the press as indicated by line 3—3 of Figure 1.

Figure 4 an enlarged fragmentary sectional elevation showing one form of the lock and release mechanism for the baling press ejection doors, the section being indicated by line 4—4 of Figure 2.

Figure 5 a sectional plan view of the same, the section being indicated by line 5—5 of Figure 4.

Figure 6 an enlarged fragmentary plan view of the spring controlled panel closure latch means; and

Figure 7 a detail plan view, partly in section, of my preferred form of door for the bale ejection openings of the box.

Referring by characters to the drawings, 1 indicates the end walls of the box and 2 the side

2

walls of the same forming, in conjunction with the walls 1, bale ejection openings. These openings are provided with closure doors 3 hinged to the side walls. The doors when closed, in effect, form the sides of the baling box and, in this instance, each of them is locked by means of pairs of apertured lugs 4 secured to the end walls 1, as best shown in Figures 1 and 4 of the drawings. These lugs are engaged by apertured ears 4' which extend from the free ends of the doors. When the doors are closed they are locked to the end walls by pins extending from a rod 5 which is reciprocatively mounted in lugs 6 that extend inwardly from the box side walls 2. When it is desired to unlock the swinging doors, a foot pedal 7, pivoted to the bottom of the press and extending outwardly therefrom, is manipulated to lift the rods, it being understood that said rods in their locked positions may move downwardly through their weight or through spring pressure.

The top portion of the press box has secured thereto a rectangular housing 8 having a filling opening 9 therein communicating with the baling press box, and reciprocatively mounted in the box is a skeleton press platen 10 in angle iron form. The vertical flanges of the angle iron form a press platen filling opening 11, which filling opening is closed by a centrally disposed panel 12 which panel, in effect, constitutes a part of the platen.

As best shown in Figures 2 and 3 of the drawings, the panel is connected to the vertical flange 11 of the platen by hinges 13, it being understood that the platen and associated panel are provided with the usual spaced slats, as is also the bottom of the press box, for convenience in baling.

The housing 8, at its ends, has journaled therein a pair of threaded rods 14 aligned over the angle iron edges of the platen 10 which is provided with ears for pivotal connection to pairs of links 15, the opposite ends of which are pivoted to nuts 16, which nuts are slotted at their upper edges for sliding engagement with strips 17 that extend downwardly from the housing wall, as best shown in Figure 3 of the drawings, the nuts being in threaded union with the threaded rods 14, whereby said nuts are held against turning when they move back and forth upon the rods which are 50 rotatable.

From the foregoing description, it will be noted that a comparatively shallow housing 8 is mounted above the press box 1 and it carries not only the reciprocative platen but all actuating mechanism for the platen. Hence, said housing and

associated parts can be conveniently assembled or bodily removed for repairs or adjustments and, furthermore, such assemblage materially simplifies and reduces manufacturing cost. Furthermore, the actuating structure assembled in a shallow housing materially reduces the height of the press, which is an advantage over presses of this general type, when it is borne in mind that these presses extend at a comparatively great height, which take up space and require a high ceiling.

As shown in Figures 1 and 2, the rods 14 at one end have secured thereto pulleys 18, which pulleys are in belt connection with pulleys 19 mounted on a stud shaft 20, that is journaled in an end wall 21 forming part of a chamber A extending from the end walls 1 of the baling press box, it being understood that the companion chamber A at the opposite end of the press serves as a housing for the swinging doors locking mechanism.

The wall 21 associated with the driving mechanism of the threaded rods has secured thereto an offset casing 22, which casing has mounted therein, upon the baling box floor, an electric motor 23. The electric motor, under suitable control, imparts driving power to the threaded rods 14 by means of a pulley and belt connection B. The spring controlled latch, which locks the hinged panel portion of the platen, comprises a flanged plunger 24 slidable in track rails 25 secured to the bed of the panel 12. The rear end of the plunger is provided with a socket into which a coil spring 26 is fitted, the opposite end of the latter being in engagement with the flange web 11, which is provided with a spring retaining tongue 11', as best shown in Figure 6 of the drawings. The front end of the plunger is tapered and locks under a corresponding tapered tooth 27.

The top face of the latch plunger 24 has secured thereto a vertically extended handle 28 which projects the feed opening 9 of the housing 8, to permit free access thereto, as indicated in Figures 1 and 3 of the drawings.

In the operation of the baler, when it is desired to charge the same with the product to be baled, the latch handle 28 is moved backward (as indicated in dotted lines in Figure 3). The latch handle is then utilized to swing open the panel to the position indicated in dotted lines, Figure 3, thus clearing the filling opening in the platen, whereby the material is freely fed into the box. The panel 12 is then swung back to the position shown in full lines, Figure 3, whereby the platen is closed throughout its surface, due to the spring controlled latch snapping into its locked position.

Owing to the fact that the panel 12 is hinged, in the event the material for baling should mound, it may readily be pressed downward for closure, without snarling or clogging at its edges.

It is further emphasized that the actuating sets of toggle links 15 are positioned under and beyond the sides of the filling opening of the housing, whereby said links and other actuating mechanism are protected, as said parts are all beyond the sides of the housing filling opening.

In order to complete the baling operation, the motor is started, to impart rotation to the threaded rods, whereby the nuts, now in the position shown in Figure 1, will spread apart and the links 15, in spreading, will cause the platen 10 to move

downwardly to its limit position, indicated in dotted lines, Figure 1, whereby complete compression of the product is effected. Thereafter the doors, closing the bale ejecting openings, are moved from their locked positions clear of said openings. The compressed bale is then confined by cords or runners in the usual manner and said bale is then ejected. The motor is thereafter started in reverse to move the platen upwardly to the position shown in Figure 1. Thus it will be seen that all of the mechanism is self contained within the area of the baling press.

While I have shown and described the press doors 3 fully as to detail, it should be understood in practice I prefer to utilize sliding doors such as illustrated in Figure 7 of the drawings, which sliding doors are particularly advantageous, due to the fact that they may be opened and closed within the confines of the side walls of said baler. As will be seen in Figure 7, the door 3' is slideable in channel strips 29 carried by the baler side walls 2.

While I have shown and described one form of my invention specifically as to detail, it is understood that I may vary the structural features within the scope of the claims.

I claim:

1. A baling press comprising a box, oppositely disposed ejecting doors therein, a housing having a filling opening therein secured to the top of the box, a platen reciprocatively mounted in the box embodying an angle iron frame, a panel hinged to the angle iron frame, a locking plunger mounted upon the panel engageable with the angle iron frame, threaded rods journaled in the housing above the sides of the angle iron frame, a pair of nuts mounted upon each rod, guides for the nuts extending from the housing, and pairs of links connecting each nut with an end of the aforesaid angle iron platen frame.

2. A baling press comprising a box, oppositely disposed door closure openings in the box, a shallow housing secured to the top of the box having a filling opening therein, an angle iron skeleton platen frame mounted in the box, providing a filling opening, a panel for closing the platen filling opening hinged to one side of the angle iron frame, a latch carried by the panel for locking engagement with the other angle iron side of the platen frame, strips depending from the housing over the sides of the angle iron platen frame, threaded rods journaled in the housing below the strips, a pair of nuts mounted upon each rod and slidably engaging the housing strips, and a pair of laterally extended links connecting each nut with an end of the angle iron platen frame.

GEORGE C. SCHLEY.
